(57) **CLAIM**

(21) Appl. No.: **29/328,581**

The ornamental design for a strategic pattern building board game with ejecting feature, as shown and described.

(22) Filed: **Nov. 26, 2008**

DESCRIPTION

(51) LOC (9) Cl. **21-01**

FIG. 1 is a perspective view of the strategic pattern building board game with ejecting feature of the instant invention;

(52) U.S. Cl. **D21/337**

FIG. 2 is a top plan view thereof;

(58) Field of Classification Search D21/334-368;

FIG. 3 is a bottom plan view thereof;

273/236-288

FIG. 4 is a front elevational view thereof;

See application file for complete search history.

FIG. 5 is a rear elevational view thereof;

273/236-288

FIG. 6 is a right side elevational view thereof; and,

5,154,428 A 10/1992 Woolhouse

FIG. 7 is a left side elevational view thereof.
